DOOR LATCH

William Albert Gill, Dartmouth, England

Application March 1, 1950, Serial No. 147,085

Claims priority, application Great Britain
March 1, 1949

3 Claims. (Cl. 292—170)

1

This invention relates to latches, more particularly for doors and the like, and has for its principal object the provision of a novel and improved form of door latch which offers advantages over those latches which are known and used at the present time.

A more specific object of the invention is the provision of a door latch having a spring-urged locking bolt and catch means for positively retaining the bolt in its locking position until the said catch means are released by the operation of a handle or key.

A further object of the invention is the provision of such a latch having a release member which is automatically operated as the door nears its closed position to release the catch and thus allow the door to close without it being necessary to operate the handle.

Yet another object of the invention is the provision of a novel and improved means for operating a door latch, which means are particularly well adapted to be operated by pushing or pulling a handle towards or away from the face of the door.

Yet another object of the invention is the provision of such a latch operating mechanism which comprises an operating rod which is slidably mounted for movement transverse to the plane of the door and which is formed with a cam face or faces which engage an actuating member by the movement of which the latch may be released.

Further objects of the invention will become apparent from the following description, taken in conjunction with the accompanying drawings.

In the drawings:

Figure 1 is a side view, taken partly in section, showing one form of door latch constructed in accordance with the invention, one side plate of the latch casing being removed to show the internal parts;

Figure 2 is a front view of the latch shown in Figure 1;

Figure 3 is a section taken on the line III—III of Figure 1;

Figure 4 is a section taken on the line IV—IV of Figure 1;

Figure 5 is a section taken on the line V—V of Figure 1, showing the latch fitted to a door;

Figure 6 is an end view of one of the handles shown in Figure 5 for operating the latch;

Figures 7 and 7a show, in face and edge views, respectively the side cover plate which has been removed from the latch shown in Figure 1;

Figure 8 is a detail view showing part of the latch;

2

Figures 9 and 9a show in front and end views respectively a striking plate which is intended to be used in conjunction with the latch of Figures 1 to 8;

Figure 10 is a side view, partly broken away and in section, showing a modified form of latch according to the invention;

Figure 11 is a section taken on the line XI—XI of Figure 10;

Figure 12 is a section taken on the line XII—XII of Figure 10;

Figure 13 is a section taken on the line XIII—XIII of Figure 10, showing the latch fitted in a door and provided with an operating handle;

Figure 14 is a detail perspective view showing a part of the latch of Figures 10 to 13.

Referring first to Figures 1 to 9a, the latch comprises a casing 1, which consists of top, bottom and back walls, 2, 3 and 4 respectively, and of two side plates 5 and 6. The plate 6 has been removed from the latch shown in Figure 1 but is shown separately in Figure 7. This side plate is adapted to be secured to the body of the casing by means of screws passed through holes 7 in the side plate and screwed into tapped holes 8 formed in the casing. The side plate 5 may be secured to the body of the casing in a similar manner to the plate 6 or it may be welded or otherwise permanently secured to the top, bottom and back walls 2, 3 and 4.

The casing 1 is mounted on the back of a face plate 9, which plate is intended to be sunk in the edge of the door in the usual manner and to be secured in position by means of screws passed through holes 10 formed in the face plate.

The face plate 9 is formed with suitable holes to allow the projection of the ends of two bolts 12 and 13, which bolts are slidably mounted within the casing 1. The upper of these bolts 12, which is slidably mounted between the top wall 2 of the casing and a guide 14 fitted in the latter, acts as the main locking bolt. It is urged to its locking position by means of a compression spring 15 which is fitted in a bore formed in the bolt and which bears against the back 4 of the casing.

The lower bolt 13 is the release bolt. It is mounted between the guide 14 and a further guide 16 and is urged outwardly by means of a spring 17 fitted in a bore in the bolt and bearing against a block 18. This block 18 is fitted in the casing and is secured to the back wall 4 by means of a screw 19.

The projecting end of the bolt 12 is provided with a roller 21 which is fitted in a recess formed in the end of the bolt and which is rotatably mounted on a stud or pin 22. Similarly the bolt

13 is provided with a roller 23 which is mounted on a stud 24.

The locking bolts 12 is normally retained in its locking position by means of a handle-controlled catch or member 30 the upper end of which operates in a recess 31 formed in one side of the bolt 12. This catch 30 passes slidably through cut-outs formed in the guides 14 and 16 and is provided at its lower end with a horizontal platform or laterally extending part 32. A spring 33 urges the catch 30 upwardly into the position in which its front upper corner 34 engages the step 35 of the bolt 12.

The catch 30 is provided at its upper end with an extended tooth 37 which is formed on its underside with a cam face 38. When the catch 30 is drawn down, this cam face 38 engages a stud 39 which is provided on the bolt 12. This engagement takes place at the time when the corner 34 of the catch 30 clears the bolt 12 so that continued downward movement of the catch has the effect of retracting the bolt.

A cam lever 40 is pivoted at 41 to a lug projecting from the back of the face plate 9. The end of this lever or part 40 rests on the platform 32, while its upper portion is formed with a cam face 42 which is adapted to be engaged by the inner end of the release bolt 13.

Referring now to Figures 9 and 9a, this shows the striking plate which is used in conjunction with the latch of Figure 1. This striking plate 50 which is intended to be attached to the door frame by means of screws (not shown) passed through screw holes 51 formed in the plate, is formed with a central opening 52. It will be noted that the upper portion 53 of this opening, which is intended to receive the locking bolt 12, is narrower than the lower portion 54 which is intended to receive the release bolt 13, while the plate is provided with side lips or extensions 55 which are adapted to be engaged by the release bolt 13 before the locking bolt strikes the edges 56 of the striking plate.

It will thus be seen that as the door closes, the release bolt 13, striking the lip 55, will be operated to disengage the catch 30 from the bolt 12 before this latter bolt strikes the edge 56 of the striking plate. Thus the bolt 12 can move inwardly to permit the door to close. Should the swelling of the door or other causes result in the locking bolt not retracting easily when it engages the striking plate, the movement of the cam tooth 37 will, of itself, result in the continued movement of the release bolt 13 retracting the locking bolt 12.

A stud 58, the purpose of which will be explained, is provided on the bolt 13 engaging in a slot 59 formed in the underside of the bolt 12. The slot 59 is made of such a length as to ensure that the catch 30 is disengaged from the end of the bolt 12 before the stud 58 engages and operates the latter. The two bolts thus have a lost-motion connection.

Owing to the provision of the rollers 21 and 23 on the ends of the bolts 12 and 13 an opening pressure applied to the door would be sufficient to force in the bolts but for the catch 30 which locks the bolt 12. It will be appreciated that the widened portions 54 of the opening in the striking plate 50 ensure that when the door is closed the release bolt 13 cannot be forced in to release the catch 30 by engagement with the striking plate. In order to open the door, therefore, it is necessary to operate a handle provided for the purpose.

Such a handle is shown at 61 in Figures 5 and 6 while a second similar handle 62 is provided on the opposite side of the door, it being understood that the latch described is intended for use on a double-acting or swing door.

The handle 61 is pivoted at its lower end to a link 63 which in turn is pivoted at 64 to a bracket 65 mounted on the face of the door. Alternatively, the handle 61 could be pivoted directly to the bracket 65 providing that a small working clearance is allowed at the joint to permit the angular movement of the handle.

At its upper end the handle 61 is pivoted at 66 to a boss 67 which is screwed on to the end of an actuating rod 68 which passes through the door and through the latch casing mounted therein. The other end of this rod 68 is also screwed for attachment to the boss 69 (corresponding to the boss 67) to which the handle 62 is connected at its upper end. Flanged sleeves or guards 70 and 71 which are attached to the door surround the ends of the rod 68 and the necks of the bosses 67 and 69.

Where the actuating rod 68 passes through the latch casing it is provided with an enlarged part 73 of square external section. This part 73 of the rod 68 is formed with a generally arcuate cam recess 74 in which an actuating ball or element 75 engages, this ball operating in a vertical bore formed in the block 18.

Compression springs 76 and 77 surround the ends of the actuating rod 68 between the body of the latch casing and the bosses 67 and 69 of the handles 61 and 62. These springs serve to centre the actuating rod 68 and to return it to the position shown after it has been displaced in either direction by a push or a pull applied to one of the handles 61 and 62.

The ball 75 rests on the head 80 of a hollow stud 81 the stem of which is fitted loosely in a hole formed in the platform 32. A compression spring 82 forces the stud 81 upwardly and keeps the ball 75 in engagement with the actuating rod 68.

It will be clear that when either of the handles 61 and 62 is operated either inwardly or outwardly the effect will be to force the ball 75 and with it the catch 30 downwardly, thus disengaging the latter from the locking bolt 12. Mere pressure on the door should then be sufficient to force the bolt 12 (and also the bolt 13) inwardly, thus allowing the door to open, but should it fail to do so owing, for example, to the swelling of the door, the engagement of the cam tooth 37 with the stud 39 will ensure the retraction of the bolt 12, which, by engaging the stud 58, will retract the bolt 13.

Owing to the movement permitted between the stud 81 and the platform 32 the former will maintain the ball 75 in engagement with the rod 68 when the platform 32 is depressed by the bolt 13 and lever 40 during the closing of the door.

It would be possible for the lower ends of the springs 33 and 82 to rest on the bottom 3 of the casing, but in the construction shown the lock is provided with an additional key-operated catch 90 and the lower ends of these springs are arranged to press on a platform or projection 91 provided on this catch in order to control the latter.

The catch 90 extends up within the casing beside the catch 30 and its upper end is adapted to engage the step or shoulder 35 of the bolt 12 in a similar manner to the catch 30.

The catch 90 is operated by means of a tongue

92 which engages a cam face 93 formed on the underside of a projecting arm portion 94 of the catch. When the tongue 92 is in the position shown in Figure 1 the catch 90 is in its lower position so that its upper end is clear of the bolt 12. When, however, the tongue 92 is turned in a clockwise direction (Figure 1) towards the end 95 of the cam surface 93 the catch 90 is raised and locks the bolt.

The tongue 92 may be operated by any suitable key, or other member fitted in a slot 96 cut in the cylinder 97 carrying the tongue 92 and it may be controlled by any suitable lever, cylinder or other lock mechanism. This mechanism may be provided as an integral part of the latch or the slot 96 may be designed to receive the operating rod of a separate lock, for example one of the cylinder type, mounted in or on the door.

Figures 10 to 14 show a modified form of latch which is of a simplified and cheaper construction. This latch comprises a casing 101 which is mounted on the back of a face plate 102. It may be cast integrally with the latter, if desired.

The casing 101 is formed with two parallel bores 103 and 104, of circular cross-section, within which are slidably mounted two bolts 105 and 106 respectively. The ends of these bolts carry rollers 107 and 108 respectively and project through suitable apertures formed in the face plate 102.

The upper bolt 105, which is the locking bolt, is urged to its locking position by means of a spring 109 which is fitted in a bore 110 formed in the bolt and which reacts against the base of the bore 103.

Similarly the bolt 106, which is the release bolt, is urged outwardly by means of a spring 111 which is fitted in a bore 112 formed in the bolt. The rear end of the spring 111 abuts against a catch 113 (see also Figure 14) which is slidably mounted in suitable recesses formed in the casing 101.

The upper end of the catch 113 is adapted to engage the rear end of the locking bolt 105, while at its lower end the catch 113 is provided with a cross piece or part 114, the upper surface of which is of rounded or cam shape and engages the rear end of the bolt 106. The vertical portion or stem of the catch 113 passes through a slot 115 formed in the rear part of the bolt 106, the length of this slot being sufficient to allow the bolt 106 to be fully retracted. It will be seen that as the release bolt 106 is pressed inwardly its cam-shaped inner end engages the cam surface of the cross piece or element 114 and thus forces the catch 113 down to release the locking bolt 105.

The movement of the bolts 105 and 106 is limited by a pin 116 which is fitted in a transverse bore formed in the casing 101 and which engages in slots 117 and 118 formed in the under and upper sides, respectively, of the bolts 105 and 106.

The catch 113 is normally held in its upper position by means of a pair of small springs 119 which are fitted beneath the cross-piece 114.

As in the case of the latch described with reference to Figures 1 to 8 the latch of Figures 10 to 14 is double-acting and is intended to be mounted on a swing door provided with a handle on each side. Figure 13 shows the latch fitted to a door, one only of the handles being shown at 120.

This handle 120 is pivoted at its lower end (not shown) to the door in a similar manner to the

handle 61 of Figure 5. At its upper end the handle 120 is pivoted at 121 to a boss 122 which is screwed on the end of an actuating rod 123 which passes through the door and through the latch casing. The boss 122 is slidably in a socket 124 mounted on the face of the door and is urged outwardly by means of a spring 125 which is fitted in the socket and extends into an annular recess 126 formed in the boss 122.

There is an exactly similar handle assembly (including a spring corresponding to the spring 125) on the other side of the door attached to the other end of the rod, 123, and the two springs tend to return the rod in its central position.

Where the rod 123 extends through the latch casing it passes through a cam sleeve 130 which is slidably mounted in a transverse bore formed in the casing 101. Two spacing sleeves 132 are fitted on the rod 123, clamped between the bosses 122 and the cam sleeve 130. Consequently, longitudinal movements of the rod 123 are transmitted to the cam sleeve 130.

On its underside the cam sleeve 130 is formed with a cam recess 133 of approximately arcuate form. An actuating ball 134, which is fitted in a vertical bore 135 formed in the casing, engages in the cam recess 133.

The ball 134 is urged upwardly by means of a sleeve 136 which is acted on by a spring 137. The lower end of this spring is supported on a bottom plate 138 which is attached to the bottom of the casing 101, while its upper end bears against a tapered pin 139 which passes transversely through the sleeve 136. An end of this pin 139 engages in a cut-out 140 in the catch 113 so that the downward movement of the sleeve 136 depresses the catch 113 and disengages the latter from the locking bolt 105.

The latch of Figures 10 to 14 is intended to be used with a striking plate similar to that shown in Figure 9 and the operation of the latch will be clear from the foregoing description.

When the door is closed the locking bolt 105 is held in its locking position by the catch 113. To open the door pressure in either direction is applied to one of the handles 120. The resulting movement of the actuating rod 123 and cam sleeve 130 depresses the ball 134 and thus the sleeve 136 and catch 113. This frees the locking bolt 105 and allows the door to open when pressure is applied to it.

The operation of the release bolt 106 allows of the door being closed without touching the handles, since when the bolt 106 engages the striking plate it depresses the catch 113 and thus frees the locking bolt 105.

Both of the latches which have been described are double-acting and are suitable for use on doors of the swing type which open in either direction. The latches could, however, easily be adapted for doors opening in one direction only. In such cases a suitable stop might be provided to limit the movement of the actuating rod from its central position to one direction only.

If desired the actuating balls 75 and 134 could be replaced by rollers, while other modifications could also be made in the latch without departing from the invention.

In the preceding description the handles 61 and 120 have been assumed to be mounted vertically but they could clearly be mounted horizontally on the door or in any other desired position. They could, for example, take the form of long horizontal bars such as are provided on the doors 75 of theatres, cinemas and other places of public

entertainment, to ensure that in the event of a panic the doors will be opened by the pressure of the crowd.

I claim:

1. In combination, a latch to be secured to a door adjacent a striker plate to be secured to a door jamb, the latch including a casing, a locking bolt and a release bolt, said bolts being spaced apart in said casing and being in line with separate portions of said plate, yielding means to move each bolt in a direction to project one end thereof from the casing into a position to engage said separate portions of the striker plate when the door is closed, said ends being formed with surfaces facing in both directions for movement of the door, a catch movable into engagement with the locking bolt for the retaining of the latter in its projected position, a handle, means connecting the handle with the catch to release the catch from the locking bolt to permit inward retraction of the locking bolt by pressure exerted on the locking bolt by the striker plate as the door is opened, the release bolt being mounted to be movable independently of the locking bolt and also retractable by inward pressure exerted thereon by the striker plate as the door is closed, and the catch having a part in a position to be actuated upon inward movement of the release bolt without movement of the handle to withdraw the catch and allow retraction of the locking bolt by inward pressure exerted thereon by the striker plate upon further closing movement of the door.

2. In combination, a latch to be secured to a door adjacent a striker plate to be secured to a door jamb, the latch including a casing, a locking bolt and a release bolt, said bolts being spaced apart in said casing and being in line with separate portions of said plate, yielding means to move each bolt in a direction to project one end thereof from the casing into a position to engage said separate portions of the striker plate when the door is closed, said ends being formed with surfaces facing in both directions for movement of the door, a catch movable into engagement with the locking bolt for the retaining of the latter in its projected position, a handle, means connecting the handle with the catch to release the catch from the locking bolt to permit inward retraction of the locking bolt by pressure exerted on the locking bolt by the striker plate as the door is opened, the release bolt being mounted to be movable independently of the locking bolt and also retractable by inward pressure exerted thereon by the striker plate as the door is closed, and the catch having a part in a position to be actuated upon inward movement of the release bolt without movement of the handle to withdraw

the catch and allow retraction of the locking bolt by inward pressure exerted thereon by the striker plate upon further closing movement of the door, the means connecting the handle and the catch comprising a longitudinal movable bar extending transversely of the casing and having a cam portion and an element between the bar and the catch to be actuated by said cam portion.

3. In combination, a latch to be secured to a door adjacent a striker plate to be secured to a door jamb, the latch including a casing, a locking bolt and a release bolt, said bolts being spaced apart one above the other in said casing and being in line with separate portions of said plate, yielding means to move each bolt in a direction to project one end thereof from the casing into a position to engage said separate portions of the striker plate when the door is closed, said ends being formed with surfaces facing in both directions for movement of the door, a catch mounted to be movable transversely of said bolts, a spring in the casing engaging the catch to move the catch, into engagement with the locking bolt for the retaining of the latter in its projected position, a handle, means connecting the handle with the catch to release the catch from the locking bolt to permit inward retraction of the locking bolt by pressure exerted on the locking bolt by the striker plate as the door is opened, the release bolt being mounted to be movable independently of the locking bolt and also being retractable by inward pressure exerted thereon by the striker plate as the door is closed, the catch having a laterally extending part in a position to be actuated upon longitudinal movement of the release bolt without movement of the handle to render the catch temporarily inoperative and allow retraction of the locking bolt by inward pressure exerted thereon by the striker plate upon closing movement of the door.
